SPATULA

William John Schacht, Huntington, Ind., assignor to Schacht Rubber Mfg. Co., Huntington, Ind., a corporation of Indiana

Application June 10, 1955, Serial No. 36,465

Term of patent 14 years

(Cl. D44—29)

Fig. 1.

Fig. 2.

Fig. 3.

Fig. 1 is a fragmentary perspective view of a spatula showing my new design;

Fig. 2 is a side elevation thereof on a reduced scale; and

Fig. 3 is an enlarged section on the line 3—3, Fig. 2.
I claim:

The ornamental design for a spatula, substantially as shown.
